United States Patent Office

Des. 221,356
Patented Aug. 3, 1971

221,356

ELECTROSTATIC COPIER

Richard H. Penney, New York, N.Y., assignor to
Sperry Rand Corporation, New York, N.Y.

Filed Feb. 19, 1970, Ser. No. 21,513

Term of patent 14 years

Int. Cl. D16—05

U.S. Cl. D61—1

FIG. 1.

FIG. 2.

FIG. 3.

FIG. 4.

FIG. 5.

FIG. 1 is a front perspective view of an electrostatic copier showing the new design;

FIG. 2 is a rear elevational view thereof;

FIG. 3 is a top view thereof;

FIG. 4 is a right side elevational view thereof; and

FIG. 5 is a left side elevational view.

I claim:

The ornamental design for an electrostatic copier, substantially as shown and described.
